UNITED STATES PATENT OFFICE.

ARTHUR R. WILFLEY, OF DENVER, COLORADO.

CENTRIFUGAL PUMP.

1,346,926.

Specification of Letters Patent. Patented July 20, 1920.

Application filed June 30, 1919. Serial No. 307,799.

To all whom it may concern:

Be it known that I, ARTHUR R. WILFLEY, a citizen of the United States, residing at the city and county of Denver and State of Colorado, have invented certain new and useful Improvements in Centrifugal Pumps; and I do declare the following to be a full, clear, and exact description of the invention, such as will enable others skilled in the art to which it appertains to make and use the same, reference being had to the accompanying drawings, and to the characters of reference, marked thereon, which form a part of this specification.

15 My invention relates to improvements in centrifugal pumps.

My present improvement is especially adapted for use in that class of pumps in which the water is raised by suction, as distinguished from those pumps in which the water level is above the runner chamber, and where the passage of water into and through the pump is not dependent upon suction; though my present improvement is also adapted for use where the last named conditions obtain.

It will be understood that in a suction pump a vacuum condition must be maintained in the runner chamber; hence no air must be allowed to enter from the atmosphere. Furthermore, the style of pump to which my improvement is applied is that in which the opening in the pump casing through which the shaft passes is of such size that the shaft is free from the casing. In other words, the opening around the shaft is in communication with the atmosphere. Hence, in order that a construction of this character may be adapted for use with a suction pump, or a pump depending upon suction for drawing the water into the pump, a seal must be provided between the runner chamber and the opening around the shaft against the entrance of air when the pump is in operation.

My present construction is similar to that disclosed in my previous application, Serial No. 303,891, filed June 13th, 1919, except that in the latter construction it is assumed that the head of water is above the runner chamber, so that suction is not relied upon for drawing the water or other liquid into the pump. Hence, atmospheric air may enter around the shaft, the only desideratum

being that the water is prevented from passing out through the opening around the shaft when the pump is in operation.

But in my present construction I must prevent the atmospheric air from entering the runner chamber, otherwise the suction would be broken and the pump inoperative.

Broadly speaking, in order to accomplish the aforesaid result, I provide through the agency of centrifugal force a water seal between the opening around the runner shaft and the runner chamber, whereby the entrance of air to the latter is prevented; otherwise my construction is substantially the same as disclosed in my aforesaid application.

Having briefly outlined my improvement, I will proceed to describe the same in detail, reference being made to the accompanying drawing, in which is illustrated an embodiment thereof. In this drawing:

Figure 1 is a vertical section partly in elevation of a centrifugal pump equipped with my improvements.

Fig. 2 is a section taken on the line 2—2, Fig. 1, looking toward the right.

Fig. 3 is a section taken on the same line, looking toward the left.

Fig. 4 is a section taken on the line 4—4, looking toward the right.

The same reference characters indicate the same parts in all the views.

Let the numeral 5 designate a stationary casing upon which is mounted a chamber 6, which is connected with the main casing 7, in which the runner 8 is arranged. The runner is connected, as shown at 9, with one extremity of the shaft 10, upon which is mounted at a suitable distance beyond the runner chamber, a disk 12, located in a chamber 13 formed by a part 14, stationary with the casing and a head 15, which is secured to the part 14 by suitable fastening devices, as bolts, 16. The chamber 13 is in communication with the runner chamber through an opening 17, and also with the atmosphere when the pump is in operation, through openings 18 and 19, around the shaft, the opening 18 being between the member 12 and the shaft, and the opening 19 being between the shaft and a part 20 mounted on a flexible diaphragm 21, carried by the casing. When the pump is at rest, or inactive, a member 22 fast on

the shaft, coöperates with a packing member 23, carried by the part 20 to form a joint, which seals the chambers of the pump structure from the atmosphere. When, 5 however, the pump is in operation, this joint is opened through the instrumentality of a centrifugal governor composed of two parts, 24 and 25, and balls 26, arranged therebetween, whereby the member 24, as 10 the balls are thrown outwardly under the action of centrifugal force, is moved toward the runner chamber and carries with it a member 27, which is connected by a fastening device 28 with the part 20, which, 15 by virtue of said construction, is also moved toward the runner chamber, this movement being permitted by the flexible diaphragm 21, upon which the part 20 is mounted, as heretofore explained, thus separating 20 the packing member 23 of the part 20 from the coöoperating rib of the part 22. When this occurs it will be understood that the chamber 29 in which the part 22 is located, is in communication with the atmosphere. 25

It should be explained that the governor member 25 is fast on the shaft and interlocked with the member 24, whereby the latter rotates with the shaft and with the 30 part 25. The member 24, however, is loose on the shaft, but normally held in the position illustrated in Fig. 1, by a spiral spring 30, which engages a stop collar 31 on the shaft at one end and the part 24 at the opposite end. The part 27 has a depending projection 32, which enters a recess formed in a collar 33, having a rib 34, which enters a circumferential groove formed in the part 24, whereby the part 33 is moved in the 35 direction of the axis of the shaft by the governor member 24, but does not rotate therewith. Hence, by virtue of this construction, the movement of the governor member 24 toward and away from the runner chamber actuates the member 27 to seal and unseal the aforesaid joint by virtue of the movement imparted to the member 20. The disk 12 is secured to the runner shaft by means of a set screw 35, 40 and is provided on the face toward the runner with curved vanes 36 and on its opposite side by similar vanes 37.

The part 15 inclosing the chamber 13 is provided adjacent the shaft with a projection 38, which extends toward the disk 12 and is adjacent the inner extremities of the vanes 37. The vanes 36 are somewhat shorter than the vanes 37; hence the centrifugal force imparted to the water by 45 these vanes is somewhat less than that which is imparted by the longer vanes 37. When the pump is in operation and the joint formed by the parts 20 and 22 is opened, the air which is in communication with the chamber 29 passes through the

openings 18 and 19 around the shaft and enters the portion of the chamber 13 close to the shaft on the side of the vanes 37. This air is seeking to enter the runner chamber in response to the vacuum produced by the runner but the centrifugal force imparted to the water by the vanes 36 is sufficient to prevent the air from passing from the side of the disk 12, where the vanes 37 are located, to the opposite side. 50 In other words, the centrifugal force imparted to the water by the vanes 37 is somewhat greater than that imparted by the vanes 36, but as the air enters the chamber 13 on the side of the vanes 37, it follows the water outwardly until a balance is reached between the water and air on the side of the disk where the vanes 37 are located, and the water on the side where the vanes 36 are located. By virtue of this 55 construction, it is impossible for the air on the one side of the disk 12 to pass beyond the outer edge of the disk where a water seal is maintained to prevent the entrance of atmospheric air to the runner chamber when the pump is in operation and relying on suction to draw the water into the runner chamber.

As illustrated in the drawing, I may employ a small pipe 39, which communicates 60 with a passage 40 formed in the casing for introducing a small amount of water to the chamber 41 between the part 12 and the flexible diaphragm for the purpose of keeping the opening 18 around the shaft, for 65 instance, from becoming clogged or interrupted by sand or other foreign matter. To this end the member 18 below the shaft is recessed, as shown at 42, to allow this water to pass through into the chamber 13 and 70 thence into the runner chamber. This is an expedient which may or may not be resorted to, but, as it is an old feature and nothing is claimed herein, further detailed explanation is not deemed necessary. 75

From the foregoing description, the use and operation of my improved centrifugal pump will be readily understood.

When the pump is at rest, the parts will be in the position illustrated by Fig. 1. 80

Now, assuming that the pump is operating by suction, as soon as the shaft begins to rotate, the balls 26 of the centrifugal governor will be thrown outwardly and act upon the member 24 of the governor 85 through the medium of the connections heretofore explained, to open the joint between the parts 20 and 22, whereby the openings 18 and 19 are in communication with the atmosphere and the air entering 90 the chamber 13 around the shaft, is carried outwardly on the side of the disk 12 where the vanes are located. But a water seal is maintained around this disk since the centrifugal force of the water, acted on by the 95

vanes 36, is sufficient to balance the force imparted to the water by the vanes 37. While the amount of water on the side of the disk where the vanes 37 are located is less than that on the opposite side, the greater length of the vanes 37 plus the air pressure increases the force with which the water is carried outwardly, sufficient to balance the force of the water on the side of the vanes 36, thus preventing the water on either side of the disk 12 from passing to the other side and maintaining a water seal around the disk, which prevents the entrance of atmospheric air to the runner chamber when the pump is in operation, even though the portion of the chamber 13 in proximity to the shaft is in communication with the atmosphere.

I claim:

1. A centrifugal pump, whose casing is provided with a suction opening and an opening through which the shaft passes, said pump having a member inclosing an auxiliary chamber around the shaft, which last named chamber is in communication with the runner chamber and also with said shaft opening, a second member located in the auxiliary chamber, one of the said members being connected to rotate with the shaft, and the two members being constructed to coöperate to form a water seal between the two members at the outer portion of the auxiliary chamber to prevent the passage of air from the last named chamber toward the runner chamber.

2. A centrifugal pump, whose casing is provided with a suction opening and an opening through which the shaft passes, said pump having a member inclosing an auxiliary chamber around the shaft, which auxiliary chamber is in communication with the runner chamber and also with the said shaft opening, a second member located in the auxiliary chamber, one of the said members being connected to rotate with the shaft and having two sets of vanes, one set being on the runner side and the other set on the air inlet side, the vanes on the latter side being the longer.

3. A centrifugal pump, whose casing is provided with a suction opening and an opening through which the shaft passes, said last named opening communicating with the atmosphere when the pump is in operation, the pump having a member inclosing an auxiliary chamber around the shaft, which last named chamber is in communication with the runner chamber and also with said shaft opening, a second member located within the auxiliary chamber, one of the said members being connected to rotate with the shaft, the rotary member being constructed to drive the water outwardly in the auxiliary chamber with greater force on the air inlet side than on the opposite side.

4. A centrifugal pump, whose casing is provided with a suction opening and an opening through which the shaft passes, said shaft opening communicating with the atmosphere when the pump is in operation, the pump having a member inclosing an auxiliary chamber around the shaft, which last named chamber is in communication with the runner chamber and also with said shaft opening, a second member located within the auxiliary chamber, one of the said members being connected to rotate with the shaft, the rotary member being constructed to drive the water outwardly on the runner side and on the air inlet side with unequal force, but so proportioned as to produce a balance and form a water seal to prevent the passage of air through the said chamber toward the runner chamber.

5. A centrifugal pump, whose casing is provided with a suction opening and an opening through which the shaft passes, said shaft opening communicating with the atmosphere when the pump is in operation, the pump having a member inclosing an auxiliary chamber around the shaft, which last named chamber is in communication with the runner chamber and also with said shaft opening, a second member located within the auxiliary chamber, one of the said members being connected to rotate with the shaft, the rotary member being constructed to drive the water outwardly on the runner side and on the air inlet side with unequal force, but so proportioned on the two sides as to prevent the escape of water from the runner chamber and to seal the auxiliary chamber against the passage of air toward the runner chamber.

6. A centrifugal pump, whose casing is provided with a suction opening and an opening through which the shaft passes, said shaft opening communicating with the atmosphere when the pump is in operation, the pump having a member inclosing an auxiliary chamber around the shaft, which is in communication with the runner chamber on one side and with the said shaft opening on the other side, a second member located in the auxiliary chamber, the two members being constructed to drive the water outwardly on the runner side in the auxiliary chamber, and the air and water outwardly on the air inlet side with such force as to produce a balance of pressure and form a seal at the outer portion of the auxiliary chamber.

7. A centrifugal pump, whose casing is provided with a suction opening and an opening through which the shaft passes, said shaft opening communicating with the atmosphere when the pump is in operation, the pump having a member inclosing an auxiliary chamber around the shaft, which is in communication with the runner chamber on one side and with the said shaft opening on

the other side, a second member located in the auxiliary chamber, the two members being constructed to drive the water outwardly on the runner side in the auxiliary chamber, and the air and water outwardly on the air inlet side with such force as to produce a balance of pressure and form a seal at the

outer portion of the auxiliary chamber, to prevent the passage of air through the auxiliary chamber toward the runner chamber, 10 and to prevent the passage of water from the runner chamber through said opening.

In testimony whereof I affix my signature.
ARTHUR R. WILFLEY.
